UNITED STATES PATENT OFFICE.

BARNEY ZINDEL AND WILLIAM H. HART, OF GREEN BAY, WISCONSIN.

STEAM-BOILER FEEDER

Specification of Letters Patent. Patented Jan. 22, 1918.

1,254,185.

Application filed November 1, 1917. Serial No. 199,690.

To all whom it may concern:

Be it known that we, BARNEY ZINDEL and WILLIAM H. HART, citizens of the United States, residing at Green Bay, in the county of Brown and State of Wisconsin, have invented certain new and useful Improvements in Steam-Boiler Feeders; and we do declare the following to be a full, clear, and exact description of the invention, such as will enable others skilled in the art to which it appertains to make and use the same.

Our invention relates to improvements in feeders for steam boilers and more particularly to those which heat the feed water before injecting the same into the boiler.

The principal object of our invention is to provide a simple, inexpensive and easily installed apparatus which may well be used upon locomotives, provision being made so that throwing of the entire feeder out of use is not necessary in case of injury to certain parts thereof.

With the foregoing general object in view, the invention resides in the novel features of construction and unique combinations of parts to be hereinafter fully described and claimed, the descriptive matter being supplemented by the accompanying drawings which form a part of this specification and in which:

Figure 1 is a side elevation of a locomotive, partly in section, showing the application of our invention;

Fig. 2 is an end elevation partly in section; and

Figs. 3, 4 and 5 are diagrams showing the different courses which the feed water may be made to travel.

In the drawings above briefly described, the numeral 1 designates a locomotive boiler, 2 the smoke box at the front end of said boiler, 3 the cab at the rear end thereof, and 4 the smoke stack from said smoke box, all of these features being of well known construction.

An injector 5 is provided within the cab 3, said injector having the usual steam inlet 6, water inlet 7, and drain 8. A feed water pipe 9 leads from the injector 5 to a multiple pipe heater 10 positioned in the smoke box 2, whereas a return pipe 11 leads from said heater and discharges into the boiler at 12, said return pipe including a check valve 13 having a valved drain 14.

A second injector 15 preferably identical

with the injector 5 is provided, and a second feed water pipe 16 leads from said second injector and by means of a three way valve 17 is connected to the feed water pipe 9, both of said feed water pipes having check valves 18 between said three-way valve and their respective injectors.

A second return pipe 19 discharges at 20 into the boiler and includes a check valve 21, said second return pipe being connected to the return pipe 11 by a three-way valve 22. A by-pass pipe 23 connects the feed water pipe 9 with the second return pipe 19, said by-pass pipe having a cut-off valve 24 and said pipe 9 having a similar valve 25 between said by-pass pipe and the heater 10. At the juncture of the pipe 23 with the return pipe 19, the latter is provided with a valved drain 26.

By positioning the valve 17 as shown in Fig. 3, the injector 15 may be used for supplying feed water to the pipe 9, or if this injector should become in any way damaged, the valve 17 may be turned to the position of Fig. 4, so that the injector 5 may be used. The water from the pipe 9 may be passed through the heater 10 as indicated by the arrows in Figs. 3 and 4, but if this heater should be burned out or otherwise damaged, valve 25 may be closed and 24 opened as indicated in Fig. 5. This will prevent the passage of water through the heater and although this water will not be heated, it will be injected into the boiler through the pipe 19. By proper manipulation of the three-way valve 22, the water may be forced to travel either through the pipe 19 as shown in Fig. 3, or through pipe 11 as indicated in Fig. 4. It will be understood that the valve 22 must be closed simultaneously with closing of valve 25, when the heater 10 is to be thrown out of action.

From the foregoing, taken in connection with the accompanying drawings, it will be obvious that although our invention is of extremely simple and inexpensive nature, it will be highly efficient and durable. For these reasons, the several details shown and described are preferably employed, but we wish it understood that within the scope of the invention as claimed, numerous minor changes may well be made.

We claim:

In combination, a boiler having a smoke box at one end, a water heater in said box,

an injector, a feed water pipe leading from said injector to said heater, a return pipe from said heater into the boiler, a second injector, a second feed water pipe leading 5 from said second injector, a three-way valve connecting said second feed water pipe with the first, a second return pipe discharging into the boiler, a second three-way valve connecting said second return pipe with the first, a by-pass pipe leading from the first 10 named feed water pipe to one of said return pipes between said second three-way valve

and the delivery end of said pipe, a valve for said by-pass pipe, and a valve for said first named feed water pipe between said 15 by-pass pipe and said heater.

In testimony, whereof we have hereunto set our hands in the presence of two subscribing witnesses.

BARNEY ZINDEL.
WILLIAM H. HART.
